CLAIM

The ornamental design for a nubbin having a guide for a gripping tool, as shown and described.

DESCRIPTION

FIG. 1 is a perspective view taken from the front, the bottom and the left of the present design;

FIG. 2 is a perspective view taken from the rear, the bottom and the right thereof;

FIG. 3 is a perspective view taken from the front, the top, and the right thereof;

FIG. 4 is a front view thereof;

FIG. 5 is a rear view thereof;

FIG. 6 is a right side view thereof;

FIG. 7 is a left side view thereof;

FIG. 8 is a top view thereof; and,

FIG. 9 is a bottom view thereof.

In the Figures, broken lines depict portions of the nubbin having a guide for a gripping tool that form no part of the claimed design.

1 Claim, 7 Drawing Sheets
